UNITED STATES PATENT OFFICE.

JEFFRY FRIGON, OF BARRE, VERMONT.

REEL FOR HOSE.

988,766.

Specification of Letters Patent.

Patented Apr. 4, 1911.

Application filed April 28, 1910. Serial No. 558,268.

To all whom it may concern:

Be it known that I, JEFFRY FRIGON, citizen of the United States, residing at Barre, in the county of Washington and State of Vermont, have invented certain new and useful Improvements in Reels for Hose, of which the following is a specification.

- This invention relates to an improved reel for supporting a hose, and has for an object 10 to provide a reel with a water connection for permanent communication with the hose, and to admit of the turning of the reel to unwind the hose for use, without breaking the connection.
- 15 The invention has for another object to provide a reel with an improved bracket or support for adjustment to a wall, and through which is formed a suitable water passage communicating with the reel.
- 20 A further object of this invention is to provide a reel embracing the above enumerated advantages, comprising but few parts which are so formed and assembled as to produce a practical device and one which 25 may be economically manufactured.

For a full understanding of the invention and the merits thereof and to acquire a knowledge of the details of construction reference is to be had to the following description and accompanying drawings, in which:

Figure 1 is a vertical section through the improved reel. Fig. 2 is an end elevation of the same, partly in section. Fig. 3 is a vertical section through a slightly modified form 35 of the reel.

Corresponding and like parts are referred to in the following description and indicated in all the views of the drawings by the same reference characters.

- 40 Referring to the drawing the numeral 10 designates a wall plate which is secured against a wall 11 or like support by means of the screws 12. The plate 10 is provided upon its outer face with a block 13, the same 45 being substantially in the form of a cube and having an angular passage 14 therethrough which terminates at its ends in the lower and outer sides of the block 13. An inlet pipe 15 is disposed in threaded engagement with the block 13, communicating with the lower end of the passage 14. The pipe 15 is provided with a suitable valve 16 for controlling the passage of water to the block 13. The block 13 carries an outwardly ex-

tending and hollow axle 17. The axle 17 is 55 in the form of a length of pipe which is threaded into the outer face of the block, communicating with the upper end of the channel 14. The outer extremity of the hollow axle 17 carries an outturned annular 60 flange 18 seated against a correspondingly formed shoulder 19 formed within a chambered hub 20.

The hub comprises a cylindrical casting which is reduced at its inner end to form a 65 sleeve 21 for snug engagement about the hollow axle 17. The shoulder 19 is formed upon the outer termination of the sleeve 21 to prevent the outer displacement of the hub 20. The inner end of the sleeve 21 70 carries a stuffing box 22 engaging about the hollow axle 17 for the purpose of forming a sealed joint between the hub and the axle. The hub 20 forms an enlargement upon the outer end of the sleeve 21 and is closed 75 at its outer end by the insertion of a screw plug 23 into the same. The hub 20 is provided at its opposite ends with radial fingers 24 to which are attached the side bars or radial arms 25 forming the reel. The arms 80 25 are disposed in pairs and support therebetween a drum 26 concentric to the hub 20. The drum 26 carries a length of hose 27 which is wound thereabout and which has its inner end projecting through a suitable 85 opening 28 formed through the drum 26. A nipple 29 is threaded into one side of the hub and carries upon its outer end an elbow 30 which is suitably attached to the inner end of the hose 27. The outer end of the 90 hose 27 carries a suitable nozzle 31 for distributing the water from the hose. In this form the water passes from the valve 16 through the pipe 15 to the block 13. It is conducted from the block 13 to the hub 20 95 through the hollow axle 17. The water passes outwardly from the hub through the nipple 29 and the elbow 30 into the hose 27. As the sleeve portion of the hub is snugly and rotatably disposed about the hollow axle 100 17, the drum may be rotated without in any way interrupting the passage of the water therethrough.

In the modified form disclosed in Fig. 3 the axle 17^a supports the hub 20^a in the 105 outer end of which is disposed the valve 23^b. The valve 23^b coöperates with the hollow axle 17^a to regulate the passage of water

through the reel. In this instance the inlet valve 16 is eliminated and the water is controlled directly from the reel.

Having thus described the invention what is claimed as new is:

1. A water distributing apparatus including a plate for engagement against a wall and having a channeled block formed upon its outer face, an inlet pipe threaded into one end of the channel of the block, a hollow axle threaded into the block at the opposite end of the channel and extending outwardly from the plate, a chambered hub having a sleeve portion snugly engaging about the hollow axle and being provided with an internal shoulder, said axle having an annular flange upon its outer end for engagement against the shoulder to hold the hub in position, a reel mounted upon the hub, a nipple fitted into one side of the hub, and terminating at the periphery of the reel, and a detachable plug closing the outer end of the hub.

2. A water distributing apparatus including a hollow block having internal threads at the open ends thereof, an inlet pipe communicating with one side of the block, a hollow axle supported in the opposite side of the block and extending outwardly therefrom, a chambered hub having a reduced portion fitting snugly about the hollow axle, a detachable plug closing the outer end of the hub, radial fingers projecting in spaced relation from the hub, detachable arms secured to the fingers and radiating from the hub, a drum secured between the outer ends of the arms for supporting the hose, and a nipple fitted into one side of the hub and communicating at its outer end with the hose.

In testimony whereof, I affix my signature in presence of two witnesses.

JEFFRY FRIGON. [L.S.]
